SLIPPERSOCK

Gustave Frankel, Milwaukee, Wis., assignor to Holeproof Hosiery Company, Milwaukee, Wis.,
a corporation of Wisconsin

Application September 30, 1950, Serial No. 12,414

Term of patent 14 years

(Cl. D47—7)

To all whom it may concern:

Be it known that I, Gustave Frankel, a citizen of the United States, and resident of Milwaukee, in the county of Milwaukee and State of Wisconsin, have invented a new, original, and ornamental Design for a Slippersock, of which the following is a specification, reference being had to the accompanying drawing, forming a part thereof wherein the figure is a front perspective view of a slippersock showing my new design.

I claim:

The ornamental design for a slippersock, substantially as shown.

GUSTAVE FRANKEL.
